[57] ABSTRACT

An envelope processing machine includes envelope feed mechanism, a flight conveyor for continuously advancing a succession of envelopes received from the feed mechanism along a predetermined path through the machine, a rotary reinforcing and punching unit for simultaneously adhesively applying a reinforcing patch to the closure flap of each advancing envelope and punching a hole through the patch and the envelope closure flap, a rotary clasp attaching unit which receives a clasp and carries it into penetrating engagement with the panel of an advancing envelope and into clinching engagement with an anvil mechanically inserted into the envelope and advancing therewith, a printing mechanism for imprinting on each advancing envelope, and a delivery unit for collecting the envelopes processed by the machine.

ENVELOPE FASTENER ATTACHING MACHINE

BACKGROUND OF THE INVENTION

This invention relates in general to envelope making machinery and deals more particularly with an improved machine for attaching a closure flap fastener to an envelope. The fastener attached by the aforesaid machine comprises a clasp anchored by clinched prongs to one panel of an envelope and having bendable tabs which extend through an aperture in the envelope closure flap when the flap is closed to releasably retain the flap in closed position. The machine of the present invention may also include apparatus for applying a reinforcing patch to the envelope closure flap and for punching a hole through the patch and the closure flap to receive the bendable tabs on the associated clasp.

The purpose of the present invention is to provide an improved high-speed attaching machine of the afore-described general type for attaching a closure fastener to the envelope while the envelope is continuously advancing through the machine. A further aim of the present invention is to provide apparatus particularly suitable for in-line operation with other envelope making or processing apparatus to apply closure fasteners to envelopes received from the other apparatus at speed comparable to the maximum speeds attainable by the other apparatus.

SUMMARY OF THE INVENTION

In accordance with the present invention, apparatus is provided which includes means for receiving an envelope and continuously advancing it along a predetermined path, a clasp attaching unit which includes a prong clenching anvil, means for positioning the anvil in engagement with one panel of the advancing envelope and for advancing envelope and for advancing the anvil along at least a portion of the envelope path in engagement with the advancing envelope, a clasp attaching element supported for movement relative to the anvil for receiving a clasp which has attaching prongs thereon, and means for moving the attaching element relative to the anvil to move the clasp prongs into penetrating engagement with the one panel and clinching engagement with the anvil whereby to anchor the clasp to the one panel as the envelope continuously moves along its path. The aforesaid apparatus may comprise part of the machine which also includes a reinforcing and punching unit for simultaneously applying a reinforcing patch to the envelope closure flap and punching a hole through both the flap and the patch as the envelope continuously advances along its path through the machine.

BRIEF DESCRIPTION OF THE DRAWINGS

FIG. 1 is a side elevational view of an envelope processing machine embodying apparatus of the present invention.

FIG. 2 is a rear view of an envelope which includes a fastener of the type attached by the machine of FIG. 1.

FIG. 3 is a top view of a typical envelope clasp.

FIG. 4 is a perspective view of the clasp of FIG. 3 after the prongs thereof have been reformed or bent by the apparatus of FIG. 1.

FIG. 5 is a fragmentary sectional view taken generally along the line 5—5 of FIG. 1.

FIG. 6 is a fragmentary sectional view taken along the line 6—6 of FIG. 5.

FIG. 7 is a fragmentary sectional view taken along the line 7—7 of FIG. 5.

FIG. 8 is a fragmentary sectional view taken generally along the line 8—8 of FIG. 5.

FIG. 9 is a fragmentary sectional view taken along the line 9—9 of FIG. 1.

FIG. 10 is a fragmentary sectional view taken along the line 10—10 of FIG. 9.

FIG. 11 is a fragmentary sectional view taken along the line 11—11 of FIG. 10.

FIG. 12 is a fragmentary sectional view taken along the line 12—12 of FIG. 5.

FIG. 13 is a fragmentary elevational view similar to FIG. 6, but shows another clasp attaching wheel embodying the invention.

FIG. 14 is a top view of the attaching wheel of FIG. 13.

FIG. 15 is a fragmentary elevational view of the reinforcing and punching unit of FIG. 1.

FIG. 16 is a fragmentary sectional view taken generally along the line 14—14 of FIG. 13.

DETAILED DESCRIPTION OF THE PREFERRED EMBODIMENTS

Turning now to the drawings and referring first particularly to FIGS. 1—4, an envelope processing machine embodying the present invention and indicated generally by the reference numeral 10 in FIG. 1 is particularly adapted to attach a closure flap fastener to an envelope. An envelope provided with such a typical fastener is indicated at 12 in FIG. 2. The fastener comprises a ferromagnetic metal clasp indicated generally at 14, anchored to the envelope back panel, and provided with bendable tabs. The tabs are adapted to be bent to extend through an aperture 16 in the envelope closure flap when the flap is closed and may be again bent to releasably retain the closure flap in its closed position. A reinforcing patch 18 attached or adhered to the envelope closure flap strengthens the flap in a region surrounding the aperture 16. The clasp 14, shown in further detail in FIGS. 3 and 4 is a COLUMBIAN clasp manufactured and marketed by United States Envelope Company, Springfield, Massachusetts. It is formed from flat metal, has a base portion 20, a pair of bendable retaining tabs 22, 22, and a plurality of attaching prongs 24, 24. The prongs 24, 24 project from the base portion 20 and are adapted to penetrate at least one thickness of the material from which an envelope is made and to cooperate in clinching relation with the base 20 to anchor the clasp 14 to the envelope. In the illustrated case (FIG. 2) the clasp 14 is anchored to the envelope 12 by four prongs 24, 24 which extend through two thicknesses of paper which form a central seam extending along the envelope back panel.

The machine of the present invention is adapted for in-line operation; that is, operation in an envelope production line which includes one or more associated envelope processing machines. However, the illustrated machine 10 is set up for off-line operation to operate as an independent envelope processing unit. The envelope processing machine 10 has a frame 26 which supports a plurality of individual envelope processing units driven in timed relation by a variable speed motor 28 and includes a conventional envelope feed unit, illustrated somewhat schematically in FIG. 1 and desig-

nated generally by the reference numeral 30. The feed unit may take various forms, however, the presently preferred unit 30 comprises a stand-up folded envelope feeder and has vacuum head envelope separators (not shown) which positively pull each successive lead envelope from a stack of envelopes 12, 12 contained in a receiving chute. Envelopes are sequentially fed in back-up, open flap condition to a flight chain conveyor 32 which continuously advances each envelope along a generally predetermined path 34 through machine 10. A clasp attaching unit indicated generally at 36 and mounted on the frame 26 in alignment with the path 34 attaches a clasp 14 to the back panel of each advancing envelope 12. The illustrated machine 10 also includes a reinforcing and punching unit 38 mounted on the frame 26 in alignment with the path 34 between the attaching unit 36 and the feed unit 30. The reinforcing and punching unit applies a reinforcing path 18 to the closure flap of each envelope and also punches an aperture 16 therethrough.

The present envelope processing machine may also include one or more additional envelope processing units for performing other processing operations on an envelope as it advances therethrough. In the illustrated case, the machine 10 has a printing unit designated generally by the numeral 40 which includes an ink roll 42 and an impression roll or wheel 44. The latter wheel carries a plate (not shown) for imprinting on the envelope, as for example, for imprinting the name or trademark of the manufacturer on the envelope bottom flap as the envelope advances through the machine.

After passing through the printing unit 40, each envelope 12 is conveyed to a conventional delivery unit indicated generally at 46 which includes feed rolls and a spiral delivery mechanism which delivers envelopes in an upstanding position to a receiving table 48 for uniform accumulation. The machine may also include a counting unit which may, for example, comprise an electronic counter for activating an associated separating mechanism to group envelopes by accurate count for handling efficiency.

Clasp Attaching Unit

The clasp attaching unit comprises an independent mechanism mounted on the frame 26 for lateral adjustment relative to the flight conveyor 32 to position a clasp relative to an associated envelope carrier by the conveyor. Clasps 14, 14 successively fed from a magazine or indexing turret 50 move through a forming die which forms the prongs 24, 24 to proper clasping angle as will be hereinafter further described. A clasp 14 with prongs formed thereon is received and releasably retained by an attaching element or rotary attaching wheel 52 which moves the clasp toward the path of the advancing envelope 12. The attaching wheel 52 moves in timed relation with the moving envelope 12 and an anvil 54, best shown in FIGS. 5 and 8, which has been mechanically inserted into the envelope. The clasp prongs 24, 24 penetrate the envelope and are clenched to proper holding configuration by cooperation of the attaching wheel 52 and the anvil 54. Thereafter the anvil 54 is mechanically retracted from the envelope 12 while the envelope continues to advance along its horizontal path through the machine.

Considering now the clasp attaching unit 36 in further detail and referring particularly to FIGS. 5-12, the illustrated unit includes three prong clinching anvils 54,

54 carried by the pair of transversely spaced anvil chains 56, 56. The chains 56, 56 are supported on and driven by longitudinally spaced apart sprockets 57, 57 journaled on the frame 26. Vertically adjustable upper and lower chain guide support plates 58, 58 carried by a bracket mounted on the frame 26, as best shown in FIG. 5, carry chain guide tracks 60, 60 which guide and support the roller link chains 56, 56. A plurality of slide holders 62, 62 mounted on the chains 56, 56 extend transversely therebetween. Each slide holder 62 provides sliding support for an elongated anvil slide 64 which carries an associated anvil 54 at its free end. The anvil may comprise an integral part of the anvil slide, but preferably, and as shown, each anvil 54 comprises an insert received and retained in an associated recess in the free end of an associated anvil slide 64. At its other end each anvil slide 64 has a laterally adjustable cam follower or roller 66. A horizontal cam plate 68 mounted on the frame 26 in general horizontal alignment with the lower runs of the chains 56, 56 defines a cam track 70 which receives each roller follower 66 therein during a portion of its endless travel. Each follower 66 cooperates with the track 70 to move an associated anvil slide 64 generally toward and away from the envelope flight conveyor 32 to position an anvil in engagement with a panel of an associated envelope 12 and to retain it in engagement with the panel as the envelope travels along a portion of its path through the machine 10. Additional vertical support for the anvil slide holders 62, 62 is provided by a slide holder support indicated generally at 72 and best shown in FIGS. 5 and 7. The slide holder support 72 generally comprises a roller holder 74 supported below and in generally parallel relation to the lower runs of chains 56, 56 by a vertically adjustable stanchion 76. A plurality of rollers 78, 78 journaled for rotation about transverse axes provide rolling support for each slide holder 62 during a portion of its travel, as shown in FIGS. 5 and 7. Additional vertical support for the free end of each anvil slide 64 and the anvil 54 associated therewith is provided by a back-up slide assembly indicated generally at 80 and best shown in FIGS. 5 and 12. The slide assembly 80 includes a vertically adjustable stanchion or base 82 mounted on the frame 26 which carries a plurality parallel 84, 84 supported for rotation about transverse axes. The latter rollers support a back-up slide 86 for limited travel in one and an opposite direction parallel to the direction of envelope advance along the path 34. The back-up slide 86 is spring biased in a direction opposite to the direction of envelope travel to a first position indicated by full lines in FIG. 12 and is movable toward a second or broken line position in engagement with an associated envelope as the envelope advances through the attaching unit 36 in the direction indicated by the arrow in FIG. 12, as will be hereinafter further discussed.

60 The clasping or attaching wheel 52 comprises a generally circular disc supported for rotation about a transverse axis above and in vertical alignment with the back-up support slide assembly 80. More specifically, the attaching wheel 52 is supported for rotation by a shaft 90 journaled on a pair of transversely spaced support plates 92, 92 (one shown). The latter plates are supported for transverse adjustment relative to the machine frame 26 by a pair of support rods 94, 94 which extends transversely of the frame, as best shown in FIGS. 1 and 6. A pair of permanent magnets 96, 96 are

mounted in inserts 97, 97 fastened in diametrically opposite recesses in the attaching wheel 52, as best shown in FIG. 6. Each of the inserts defines a substantially flat peripheral surface portion of the wheel to receive and magnetically retain an associated ferromagnetic clasp 14 as will be hereinafter further discussed. A pair of retractable pins 98, 98 associated with each magnet 96 are spring biased to a projected position slightly beyond the peripheral surface of the wheel 52, as shown in FIG. 6. A pivoted cam lever 100 associated with each insert 97 carries a roller follower, and operates to retract the pins upon engagement of the follower with an arcuate cam segment 102 mounted adjacent the attaching wheel 52, substantially as shown in FIG. 6. A spring stripper 104 is fixedly mounted at a 3 o'clock position relative to the attaching wheel 52 as it appears in FIG. 6. The attaching unit 36 further includes a clasp alignment device designated generally at 106 which comprises a brush 107 mounted adjacent the peripheral surface of the attaching wheel 52 at a 9 o'clock position (FIG. 6). The alignment device also includes a pair of laterally spaced clasp alignment guides 108, 108 (one shown) mounted adjacent the peripheral surface of the wheel.

Considering now the apparatus for feeding clasps to the attaching wheel, the magazine 50, best shown in FIG. 1, is supported for rotation about a vertical axis and has 12 index stations for containing clasps 14, 14 arranged in vertically stacked relation therein. The magazine 50 is releasably retained on a support turret and may be removed therefrom by depressing and turning a handwheel 109 at the top of the magazine to release a bayonet connection (not shown) which secures the magazine to the support turret therebelow. The magazine 50 is arranged to communicate with a reserve chute 110 (FIGS. 10 and 11) located therebelow and is further arranged to index so that each of the 12 feed stations thereof may be successively positioned above and in vertical alignment with the reserve chute 110 to feed clasps thereto. A fluid cylinder 112, FIG. 1, which operates a ratchet and pawl mechanism (not shown) indexes the magazine about its vertical axis. A fiber optic sensing device 114 associated with the reserve chute 110 controls the operation of the fluid cylinder 112 to index the magazine 50. The reserve chute 110 communicates with a horizontal feed track 116 (FIGS. 9 and 10) which extends in the direction of the attaching wheel 52 and terminates immediately thereabove. Each clasp 14 is fed from the bottom of the reserve chute 110 to advance along the track 116 by a cam operated push slide mechanism which includes a vacuum holdown and which is indicated at 117 in FIG. 10. A prong forming mechanism indicated generally at 118, best shown in FIG. 11, and associated with the feed track 116, is operated by a rotary cam 120 which drives forming tools 122 and 124 to form proper prong angles on each clasp. The clasp feed mechanism further includes a vacuum holder 126 (FIG. 10) at the end of the feed track 116 immediately above the attaching wheel 52. The vacuum holder is connected to a vacuum manifold 128 shown in FIG. 9.

Envelopes successively fed by the feed unit 30 are received on the flight conveyor 32 in back-up, open flap condition. As each envelope is conveyed toward the attaching unit 36, a timed jet of air from an associated jet nozzle such as indicated at 129, FIG. 8, may be generally directed toward the closure flap to slightly spread

the mouth of the envelope to an open position to prepare it to receive an associated prong clinching anvil 54, which is moving in timed relation with the flight conveyor 32. As the roller follower 66 of the associated anvil slide 64 enters the track 70, the anvil slide 64 is driven into the open mouth of the envelope to position an anvil 54 immediately below and in engagement with the central seam of the envelope back panel whereupon the cam follower 66 dwells for a portion of its travel to retain the anvil 54 in an operative position in the envelope and in alignment with the peripheral surface of the attaching wheel 52 as the envelope 12 continuously advances along its path 34.

Clasps 14, 14 received from the magazine 50 pass downwardly through the reserve chute 110 and are successively moved into the feed track 116 by the cam operated push slide 117 and advanced along the track 116 by line pressure. When a clasp 14 enters the forming station 118 the forming tools 122 and 124 operate to form the required prong angles thereon. During each attaching cycle the push slide 117 advances one clasp into the forming station 118 and another clasp into alignment with the vacuum holder 126 where it is held suspended above the attaching wheel 52.

The attaching wheel rotates in a counterclockwise direction as viewed in FIG. 6 in timed relation to the movement of an envelope 12 through the machine. When one of the magnets 96, 96 reaches its 12 o'clock position, the spring projected pins 98, 98 associated therewith engage the formed prongs 24, 24 on the clasp held by the vacuum holder 126 and strip the clasp from the holder whereupon it is drawn into engagement with the magnet 96 and releasably retained thereon. As the attaching wheel rotates in a counterclockwise direction toward its 9 o'clock position, the clasp carried by the magnet 96 passes through the alignment device 106. The brush 107 engages the projecting prongs 24, 24 to sweep the clasp 14 toward engagement with the pins 98, 98 to assure proper alignment therewith. The alignment guides 108, 108 simultaneously laterally align the clasp with the attaching wheel 52. As the magnet 96 with the clasp 14 held thereon moves toward its 6 o'clock position and into tangential relation with the path 34 an envelope 12 with an associated anvil therein is moving in timed relation with the attaching wheel. The attaching wheel moves the clasp toward the advancing envelope and anvil to cause the clasp prongs 24, 24 to penetrate the two layers of paper at the back seam of the envelope 12 and move into clinching engagement with the anvil whereupon the prongs 24, 24 are clinched toward the clasp base 20. During the latter clinching operation, the attaching wheel 52 exerts substantial downward pressure on the anvil 54 and its associated anvil holder 64. However, the envelope front panel rests upon the back-up support assembly 80 which travels with the advancing envelope during the clinching operation. Thus, the anvil 54 is supported during the clinching operation while risk of damage to the envelope front panel is avoided. Upon completion of the clinching operation, the anvil 54 is retracted from the envelope by engagement of the follower 66 in the track 70. As the magnet 96 further advances in a counterclockwise direction toward its 3 o'clock position (FIG. 6), the roller follower on the lever 100 engages the arcuate cam segment 102 to retract the pins 98, 98. In the event of a malfunction which results in a clasp being carried through and beyond the clinching station

by the attaching wheel 52, the stripper 104 functions to strip the damage or defective clasp from the peripheral surface of the attaching wheel to avoid risk of a jam at the clasp feed station. The 12 station magazine assures continuous supply of clasps to the machine 10. The fiber optic sensing device 114 detects depletion or run out of the supply of clasps from an associated magazine station and provides a signal to actuate the fluid cylinder 112 to index the magazine 50 while the machine 10 continues to operate from the supply of clasps in the reserve chute 110. The releasably retained magazine 50 may be removed from the machine 10 when empty and replaced by a full magazine by simply depressing and turning the release knob 109. Thus, the entire supply of clasps may be replenished while the machine continues to operate from the supply of clasps contained in the reserve chute 110.

The attaching unit 36 has been illustrated with reference to a COLUMBIAN clasp, however, since the anvils 54, 54 comprise inserts, it will not be evident that the anvils 54, 54 may be removed and replaced with other anvils adapted to other prong configurations so that the machine may be readily converted to attach clasps supplied by other manufacturers.

The machine 10 has been illustrated with reference to the clasp 14 which is made from ferromagnetic material. However, it may sometimes be desirable to provide a machine for attaching a clasp made from a non-magnetic material. Referring now to FIGS. 13 and 14, another embodiment of the invention is illustrated for attaching a non-magnetic clasp and includes an attaching wheel 52a. The attaching wheel 52a is similar in most respects to the wheel 52 previously described, however, it does not have magnets corresponding to the magnets 96, 96. Instead, at least one vacuum port 130 is provided which communicates with the peripheral surface of the wheel 52a to releasably retain a clasp thereon. In the illustrated case, three such vacuum ports are shown for connection to a suitable vacuum source such as the vacuum manifold 128, FIG. 9.

Reinforcing and Punching Unit

Referring now to FIGS. 15 and 16 and considering the reinforcing and punching unit 38 in further detail, the latter unit is mounted on the frame 26 for lateral adjustment relative thereto and comprises upper and lower applicator wheels 132 and 134 respectively mounted on shafts 136 and 138 journaled in a transmission housing 140, which contains a suitable lubricant. The lower applicator wheel 134 is positioned below and generally tangent the path 34 and has a punch 142 mounted in its periphery. The shaft 138 which drives the lower applicator wheel 134 extends from the rear of the transmission housing 140 and has a coaxial sleeve 144 received and releasably retained thereon for angular adjustment relative thereto. A drive pulley 146 carried by the sleeve 144 and axially adjustable thereon is driven by a timing belt 148 connected through a drive train to the motor 28, as shown in FIG. 1.

The upper applicator wheel 132 is mounted above and in general alignment with the lower wheel 134 and generally tangent the path 34 and carries a die 150 which cooperates in working relation with the punch 142. A passageway 152 formed in the upper applicator wheel 132 opens through the face of the wheel to provide a path for discharging scrap material punched from the envelope closure flap and patch 18 in forming

the aperture 16. A plurality of radially extending vacuum ports 154, 154 open through the peripheral surface of the upper applicator wheel 132 and communicate with an arcuate vacuum chamber 156 formed in the wheel. The vacuum chamber is connected with a suitable vacuum source. Additional vacuum ports 158, 158 formed in the die 150 open through the peripheral surface thereof and also communicate with the vacuum chamber in the wheel. The upper applicator wheel 132 is driven in timed relation with the lower wheel 134 by a spur gear 160 disposed within the transmission case and in meshing engagement with another spur gear 162 mounted on the lower shaft 138.

Patch material is preferably fed to the applicator wheels from an elongated web or strip of tape 162 carried by a dispensing reel 164 mounted on the transmission housing 140. preferably, and as shown, the patch material comprises pre-gummed tape which has one surface thereof coated with a contact adhesive. The tape 162 is fed from the reel 164 over an idler roll 166 journaled on the transmission housing and is advanced by a feed roll 168. The latter roll has a serrated peripheral surface for minimal surface contact with the pre-gummed surface of the tape 162. The feed roll 168 is carried by a shaft 170 journaled in the transmission housing 140. A spur gear 172 mounted on the shaft 170 within the transmission housing meshingly engages a pinion 174 mounted on the shaft 136. The reinforcing and punching mechanism further includes a shear or rotary cutter 176 which cooperates in shearing engagement with the upper applicator wheel 132 to sever a patch such as 18 from the tape 162. The rotary cutter 176 is journaled on a shaft (not shown) parallel to the shafts 136 and 138 and driven in timed relation with the upper and lower applicator wheels by an associated gear train (not shown) disposed within the transmission housing 140.

Preferably, and as shown, the reinforcing and punching unit 38 also includes a pressure applicator mechanism indicated generally at 178 for pressing the patch 18 into engagement with the closure flap of an envelope 12 as the envelope advances along its path 34. The pressure applicator mechanism includes a drive roll 180 generally tangent to the path 34, mounted therebelow and driven by an associated gear train (not shown) located within the transmission housing 140. An adjustable pressure roll 182 is mounted above the drive roll 180 and in pressing engagement therewith.

Each envelope 12 received from the feed unit 30 is conveyed through the reinforcing and punching mechanism 38 in an open flap condition with the closure flap longitudinally aligned with the applicator wheels 132 and 134 to pass therebetween as the envelope 12 advances along its predetermined path 34. The peripheral speed of the applicator wheels 132 and 134 is substantially equal to the linear speed of an envelope 12 as it is conveyed along its path 34. However, the linear speed of the tape 162 advanced by the feed wheel 168 is substantially less than the peripheral speed of the upper applicator wheel. The leading end portion of the tape 162 is held in engagement with the peripheral surface of the applicator wheel 132 by vacuum at the ports 154, 154. Since the peripheral speed of the applicator wheel 132 is somewhat greater than the linear speed of the advancing tape, the applicator wheel 132 slips with respect to the tape 162. The upper applicator roll 132 rotates in a clockwise direction as it appears in FIG. 15.

As the die insert 150 passes the rotary cutter 176, the cutter, which is rotating in a counterclockwise direction, shears a path 18 of desired length from the leading end portion of the tape 162. The severed patch 16 is held on the peripheral surface of the die 150 by vacuum at the ports 158, 158 and advances with the die 150 at a speed equal to the linear speed of an advancing envelope 12. As the patch 18 carried by the die 150 passes through the midpoint between the upper and lower applicator rolls, the contact adhesive on the surface of the patch adheres it to the envelope closure flap. An adjustable vacuum cut-off 184 is provided to interrupt the vacuum at the ports 158, 158 as the patch passes between the upper and lower applicator rolls. The punch 142 and die 150 simultaneously operate to punch the aperture 16 through the patch 18 and through the envelope closure flap which is centered relative to the punch and die as the latter move into cooperating relation. Thereafter, the envelope 12 continues to advance along its path and through the pressure applicator mechanism 178 which presses the patch into engagement with the closure flap to assure proper adherence thereto.

We claim:

1. A machine for attaching a fastener including a clasp having a base and a plurality of attaching prongs to an envelope, said machine comprising means for continuously advancing an envelope along a generally predetermined path and a clasp attaching unit mounted in said path and including a prong clinching anvil, means for positioning said anvil in engagement with one panel of the continuously advancing envelope and for continuously advancing said anvil along at least a portion of said path in engagement with the one panel, a clasp attaching element supported for movement relative to said anvil, means for releasably retaining a clasp on said attaching element, and means for moving said attaching element relative to said anvil to move said retaining means with the clasp retained thereon toward said anvil and generally along a portion of said path with the continuously advancing envelope and anvil while said anvil is positioned in engagement with the one panel to cause the prongs of the clasp to penetrate the one panel and clinchingly engage the anvil whereby to attach the clasp to the one panel by cooperation of the base and prongs thereof while the envelope is in motion.

2. A machine for attaching a fastener to an envelope as set forth in claim 1 wherein the one panel comprises a body panel of the envelope and said means for positioning said anvil comprises means for inserting said anvil into the envelope and retaining it therein for continuous travel for some distance along said predetermined path with the advancing envelope.

3. A machine for attaching a fastener to an envelope as set forth in claim 2 wherein said means for inserting said anvil includes means for conveying said anvil along another path generally parallel to said predetermined path.

4. A machine for attaching a fastener to an envelope as set forth in claim 3 wherein said means for inserting said anvil includes camming mechanism associated with said anvil and said anvil conveying means.

5. A machine for attaching a fastener to an envelope as set forth in claim 4 wherein said anvil is supported for movement relative to said anvil conveying means and said camming mechanism includes a cam mounted

in fixed position relative to said anvil conveying means and a follower associated with said anvil for engaging said cam to move said anvil relative to said anvil conveying means as said anvil is moved by the latter means.

5 6. A machine as set forth in claim 3 wherein said anvil positioning means includes an anvil carrier supported by said anvil conveying means for movement relative thereto and generally transversely of said other path and said anvil is associated with a free end portion 10 of said anvil carrier.

7. A machine as set forth in claim 6 wherein said anvil comprises an insert releasably retained in said free end portion of said anvil carrier.

8. A machine as set forth in claim 6 wherein said 15 clasp attaching unit includes anvil supporting means disposed at the opposite side of said anvil from said attaching element for supporting said free end portion while said attaching element forces the prongs through the associated panel and into clenching engagement 20 with said anvil.

9. A machine as set forth in claim 8 wherein said anvil supporting means is supported from movement with said anvil and along said envelope path while said attaching element forces the prongs through the associated panel and into clenching engagement with said anvil.

25 10. A machine as set forth in claim 8 wherein said anvil supporting means comprises a roller support mechanism.

30 11. A machine as set forth in claim 1 wherein said clasp attaching element comprises a rotary member supported for rotation about an axis extending transversely of the direction of said envelope path.

35 12. A machine as set forth in claim 1 including means for feeding a clasp to said attaching element.

40 13. A machine as set forth in claim 12 wherein said means for feeding a clasp comprises a feed track for successively feeding clasps to said attaching element, a reserve chute for containing a supply of clasps and communicating with said feed track to supply clasps thereto, a rotary magazine supported above said reserve chute and having a plurality of feed stations for containing clasps, and means for coaxially indexing said magazine to successively position each of said feed stations above and in alignment with said reserve chute to supply clasps thereto.

45 14. A machine as set forth in claim 13 including sensing means for detecting depletion of the supply of clasps from an associated index station, and means responsive to said sensing means for indexing said magazine.

50 15. A machine as set forth in claim 1 including means for aligning the clasp in predetermined position with said attaching element as said attaching element moves relative to said anvil.

55 16. A machine as set forth in claim 15 wherein said means for aligning the clasp comprises a brush supported to engage the clasp as it moves with said clasp attaching element and toward the one panel.

60 17. A machine as set forth in claim 15 wherein said attaching element comprises an attaching wheel and said means for aligning the clasp comprises a pair of transversely spaced alignment guides mounted at opposite sides of the attaching wheel near the peripheral surface thereof.

65 18. A machine as set forth in claim 1 wherein the clasp has at least one retaining tab thereon and the en-

velope has a closure panel foldable to a closed position overlying an associated portion of the one panel and the clasp attached to the one panel, said machine having a reinforcing and punching unit mounted thereon in said predetermined path and including means for applying a patch of reinforcing material to the closure panel as the envelope is continuously advanced along said predetermined path by said advancing means, and punching means for forming a retaining tab receiving hole through the reinforcing patch and the one panel as the envelope is continuously advanced along said predetermined path by said advancing means.

19. A machine as set forth in claim 18 wherein said means for applying said patch comprises said punching means.

20. A machine as set forth in claim 18 wherein said means for applying a patch comprises a pair of applicator wheels generally tangent to said predetermined path and journaled for rotation about parallel axes extending transversely of said path.

21. A machine as set forth in claim 20 wherein said pair includes a lower applicator wheel and an upper applicator wheel supported above said lower wheel and in general vertical alignment therewith.

22. A machine as set forth in claim 21 wherein said 25 punching means includes a punch mounted on one of said applicator wheels and a die for mating engagement with said punch and mounted on the other of said applicator wheels.

23. A machine for attaching a fastener including a clasp having a base and a plurality of attaching prongs to an envelope, said machine comprising means for continuously advancing an envelope along a generally predetermined path, and a clasp attaching unit mounted in said path and including a prong clinching anvil, means for positioning said anvil in engagement with one panel of the advancing envelope and for advancing said anvil along at least a portion of said path in engagement with the one panel, a rotary clasp attaching member supported for rotation about an axis extending transversely of the direction of said envelope path, means for releasably retaining a clasp on the peripheral surface of said attaching member with the groups of the clasp projecting generally radially outwardly from said attaching member, and means for moving said attaching member relative to said anvil to move said retaining means with the clasp retained thereon toward said anvil and generally along a portion of said path with the envelope and said anvil while said anvil is positioned in engagement and advancing with the one panel to cause the prongs of the clasp to penetrate the one panel and clinchingly engage the anvil whereby to attach the clasp to the one panel by cooperation of the base and prongs thereof.

24. A machine as set forth in claim 23 wherein said clasp is comprised of magnetic material and said means for releasably retaining said clasp is further characterized as magnetic means.

25. A machine as set forth in claim 13 wherein said magnetic means comprises a permanent magnet mounted in the periphery of said disc.

26. A machine for attaching a fastener including a clasp having a base and a plurality of attaching prongs to an envelope, said machine comprising means for continuously advancing an envelope along a generally predetermined path, and a clasp attaching unit mounted in said path and including a prong clinching

5 anvil, means for positioning said anvil in engagement with one panel of the advancing envelope and for advancing said anvil along at least a portion of said path in engagement with the one panel, a clasp attaching element supported for movement relative to said anvil, means for releasably retaining a clasp on said attaching element, means for feeding a clasp to said attaching element, said feeding means receiving the clasp with the prongs and the base thereof disposed in a common plane and including means for bending each of the prongs to a position generally normal to the base thereof before feeding the clasp to said attaching element, and means for moving said attaching element relative to said anvil to move said retaining means with the 10 clasp retained thereon toward said anvil and generally along a portion of said path with the envelope and said anvil while said anvil is positioned in engagement and advancing with the one panel to cause the prongs of the clasp to penetrate the one panel and clinchingly engage the anvil whereby to attach the clasp to the one panel by cooperation of the base and prongs thereof.

15 27. A machine as set forth in claim 26 wherein said clasp attaching element includes means for transferring the clasp from said feeding means to said receiving and releasably retaining means as said clasp attaching means moves relative to said feeding means.

20 28. A machine as set forth in claim 27 wherein said transferring means comprises pin means carried by said clasp attaching element for engaging the clasp to strip it from said feeding means as said attaching element moves relative to said feeding means.

25 29. A machine for attaching a fastener including a clasp and a reinforcing patch to an envelope, the patch being cut from an elongated strip of reinforcing material, the envelope having body panels and a closure panel foldable to a closed position overlying an associated portion of one of the body panels, the clasp having a base, a plurality of attaching prongs and at least one retaining tab, said machine comprising means for continuously advancing an envelope along a generally predetermined path, a clasp attaching unit mounted in said path and including a prong clinching anvil, means for positioning said anvil in engagement with the one body panel of the advancing envelope and for advancing said anvil along at least a portion of said path in engagement with the one panel, a clasp attaching element supported for movement relative to said anvil, means for releasably retaining a clasp on said attaching element, means for moving said attaching element relative to said anvil to move said retaining means with the clasp retained thereon toward said anvil and generally along a portion of said path with the envelope and said anvil while said anvil is positioned in engagement and advancing with the one panel to cause the prongs of the clasp to penetrate the one panel and clinchingly engage the anvil whereby to attach the clasp to the one panel by cooperation of the base and prongs thereof, and a reinforcing and punching unit for applying the patch to the closure panel and forming a tab retaining hole through the patch and the closure panel as the envelope is continuously advanced along said predetermined path by said advancing means and including one applicator wheel journaled for rotation about an axis extending transversely of said path and generally tangent to said path, said reinforcing and punching unit including means for feeding a leading end portion of the strip onto said one applicator wheel, means for releasably retaining the

leading end portion on said one applicator wheel, and means for serving the patch from the leading end portion as said one applicator wheel rotates about its axis and relative to said path, said reinforcing and punching unit including punching means for forming the tab retaining hole.

30. A machine as set forth in claim 29 wherein said means for releasably retaining said leading end portion comprises vacuum means.

31. A machine as set forth in claim 29 wherein said feed means comprises means for feeding said leading end portion onto the peripheral surface of said one wheel at a linear speed substantially less than the peripheral speed of said one wheel.

32. A machine as set forth in claim 31 wherein said peripheral speed is substantially equal to the linear speed of said advancing means.

33. A machine as set forth in claim 29 wherein said severing means comprises a rotary cutter journaled for rotation about an axis parallel to the axis of said one wheel to cooperate in shearing engagement with said one wheel.

34. A machine for attaching a fastener including a

clasp having a base and a plurality of attaching prongs to an envelope, said machine comprising means for continuously advancing an envelope along a generally predetermined path, and a clasp attaching unit 5 mounted in said path and including a prong clinching anvil, means for positioning said anvil in engagement with one panel of the advancing envelope and for advancing said anvil along at least a portion of said path in engagement with the one panel, a rotary clasp attaching member supported for rotation about an axis extending transversely of the direction of said envelope path, vacuum means for releasably retaining a clasp on said attaching element, and means for moving said attaching element relative to said anvil to move said retaining means with the clasp retained thereon toward said anvil and generally along a portion of said path with the envelope and said anvil while said anvil is positioned in engagement and advancing with the one panel to cause the prongs of the clasp to penetrate the one panel and clinchingly engage the anvil whereby to attach the clasp to the one panel by cooperation of the base and prongs thereof.

UNITED STATES PATENT OFFICE
CERTIFICATE OF CORRECTION

Patent No. 3,893,381 Dated July 8, 1975

Inventor(s) William A. Chapman and John J. Crowley

It is certified that error appears in the above-identified patent and that said Letters Patent are hereby corrected as shown below:

Col. 1, line 49, "thee" should be --the--.

Col. 3, lines 25 and 26, "geneally" should be --generally--.

Col. 4, line 48, "evelope" should be --envelope--.

Col. 5, line 48, "diection" should be --direction--.

Col. 5, line 51, "to advance along" should be --to and advanced--.

Col. 6, line 66, "can" should be --cam--.

Col. 7, line 24, "manufactures" should be --manufacturers--.

Col. 7, line 35, "magents" should be --magnets--.

Col. 8, line 15, "tap" should be --tape--.

Col. 8, line 17, "preferably" should be --Preferably--.

Col. 13, line 2, "serving" should be --severing--.

Col. 14, line 18, "positoned" should be --positioned--.

Signed and Sealed this
twenty-fourth Day of February 1976
